(57) **CLAIM**

The ornamental design for a rodent trap, as shown and described.

DESCRIPTION

FIG. 1 is a front perspective view of the rodent trap showing my new design;

FIG. 2 is a rear perspective view thereof;

FIG. 3 is a top view thereof;

FIG. 4 is bottom view thereof;

FIG. 5 is a left side view thereof;

FIG. 6 is a right side view thereof;

FIG. 7 is a front view thereof; and,

FIG. 8 is a rear view thereof.

The broken lines are show for illustrating environmental structure and do not form part of the claimed design.
